SIGNAL TRANSMISSION DEVICE

Claude Jean Clayette, Paris, France

Application February 23, 1939, Serial No. 258,090

4 Claims. (CL 178—35)

The present invention relates to telegraphic printing systems for arrhythmic transmission.

The object of the present invention is to provide a transmitting system in which the position of each character is defined by means of a relatively small number of signals, the relationship of which with the displacements of the character carrier is simple.

A preferred embodiment of the present invention will be hereinafter described, with reference to the accompanying drawing, given merely by way of example, and in which:

Fig. 1 diagrammatically shows a developed cylindrical surface on which the characters are arranged in a system of rectangular coordinates, being all located on the same side of the diagonal line at 45° passing through the origin, in order to avoid any ambiguity;

Fig. 2 is a diagrammatical view showing, in perspective, a particular embodiment of an apparatus according to the invention.

As the transmission of the signals corresponding to a character in a given code is effected through means which are always the same in all telegraphic systems, I will not describe the emitting means, which are well known to any person skilled in the art.

At the receiving station, a relay 1, fitted with an armature 2, which receives the line signals, controls the movement of shaft 3, driven by a motor 4 through the intermediate of a friction clutch 5.

Shaft 3, through the intermediate of escape-
ment 6, turns through an angle corresponding to one-half of a revolution for each movement of the armature 2 of relay 1. Shaft 3 carries a cam 7 on which bear the noses 8a and 8b of sliding members 9a and 9b provided, at their respective ends, with hooked levers 10a and 10b.

Under the action of the respective springs 11a or 11b, each of these levers 10a and 10b, when its end 8a or 8b is released by cam 7, engages its other end in the threads of a screw 12 which turns with a continuous movement of rotation.

It will be readily understood that, if one of the noses of levers 10a and 10b drops into one of the threads of 12, sliding member 9a or 9b is moved toward the left hand side of the device, for the whole of the time of transmission of a signal. Then, at the end of the signal, it is released by cam 7 which will have turned through an angle corresponding to half a turn, and it is brought back to its initial position by the corresponding spring 13a or 13b.

The lower ends of 10a, 10b are therefore moved distances proportional to the duration of the signals.

For all signals, they will be moved at least as far as abutments 14a, 14b. Only for the long signals, will they be moved as far as the abutments 15a and 15b.

It will be readily understood that only one of the sliding members can be driven at a time, the other being then at rest.

The shaft 16 of cylinder 17, which carries the printing characters, is driven, through friction clutch 18, by a shaft 19, which is given a continuous movement through motor 4, pinions 20, 21, and shaft 22 and pinions 23 and 24.

On shaft 16, there is fixed an escapement wheel 25 which includes a number of teeth equal to the number of angular positions of the printing cylinder.

Shaft 16 also includes a square portion 26 on which is slidable a sleeve 27 rigid with the printing cylinder 17. The rear part of this sleeve carries a screw thread adapted to cooperate with the pointed end of a lever 30, and the middle part carries a plurality of annular grooves corresponding to the number of axial positions of the printing cylinder.

The whole of sleeve 27 and cylinder 17 can be moved in the rearward direction by a spring 30 and a lever 46. Abutments 14a, 14b, provided on a piece provided with a projection 29, and actuated by levers 10a, 10b, respectively, will permit the escape of one tooth of ratchet wheel 25.

Opposite screw thread 27, there is a lever 30 the pointed end of which constitutes a kind of nut element engaged in said screw threads. During the rotation of 16, sleeve 27 and cylinder 17 are therefore driven with a helical movement as long as 30 engages 27.

At the time of the first long signal, one of the sliding members 9a or 9b acts on abutments 15a, 15b which carry nose 31. Shaft 32 is driven by motor 4 through pinions 20, 21, shaft 22, pinions 36 and 35, shaft 34, and friction clutch 33.

Shaft 32 carries a two-position stopping disc 37, released for half a turn by the movement of abutments 15a and 15b.

During the first half-turn, a cam 38 acts on the nose of lever 30, so that the nose of this last mentioned lever is released from the screw thread 27, and a second nose 39 comes to engage the corresponding groove of sleeve 27.

The movement of the printing cylinder 17 for

the following signals will be reduced to a rotary displacement.

The second long signal which indicates the end of the combination and corresponds to the printing, and which acts on abutments 15a, 15b, as above, releases shaft 32 for a second half-revolution.

During this rotation, a cam 40 acts upon the end of a lever 41 carrying the printing wheel 42 which carries the paper ribbon on which the character is to be marked. Consequently, this character is printed when the cylinder 17 is finally stopped.

Simultaneously, a cam 43, acting on lever 14a, disengages the nose 29 of the escapement 25, 15 the latter engaging on the upper end of lever 44.

The shaft 16 of the printing cylinder 17 can then turn freely until cam 45 releases the nose 29 of pawl 44 on which it rested, thus stopping, through its escapement, shaft 16 in its starting 20 position.

Simultaneously, as shaft 32 has finished its second half-turn, it has moved levers 30 and 39 through cam 38, thus releasing sleeve 27, which is rigid with the printing cylinder 17, and the latter is moved backward under the action of its spring 28 and lever 46.

In order to maintain the relative positions of shafts 32 and 16, the latter, that is to say shaft 16, carries a cam 47 which actuates the stopping lever 48, on which the cam 49 of shaft 32 comes to be stopped.

The operations of inking the paper, moving it forward, and reverting, can be ensured through any suitable conventional means.

I will now describe, by way of example, the printing of a letter transmitted to the receiving device, say, for instance, letter O.

As shown by Fig. 1, which diagrammatically illustrates the developed surface of cylinder 17, the coordinates of this letter are:

In the direction of the axis of ordinates, 3, since the ordinates of all the letters of the first lower row (including A, B, C, D, E, F, G) are 1;

In the direction of the axis of abscissas, 5, since the abscissa of the first vertical column on the left (including only letter A) is 2.

Therefore, the coordinates of letter O being 5 in abscissas and 3 in ordinates, I will first transmit a series of three signals (corresponding to the smaller of these two coordinates), and then a series of two signals (corresponding to the difference between these two coordinates).

The first series of signals will move cylinder 17 helically (owing to the engagement of the end of lever 30 in screw thread 27) a distance corresponding to three rows of characters, thus bringing opposite printing member 42 the point n preceding the printing character N.

On the other hand, as above explained, the last signal of each series is a long signal, so that the last signal of this series of three will be a long signal, which disengages the end of lever 30 from screw thread 27 and engages the end of finger 39 into one of the annular grooves of the sleeve rigid with cylinder 17, so that now, this cylinder can only turn about its axis, without any axial movement.

The second series of signals is then transmitted. As above stated, it is of two signals. It produces an angular displacement of cylinder 17 of an amplitude corresponding to two columns of characters, and the character positioned opposite printing member 42 becomes O.

The succession of the operations which produce this result is the following:

Initially, all the parts are in the position shown by Fig. 2 (with the difference that the origin of the coordinates of cylinder 17 is located opposite printing member 42). The first series of signals is transmitted, including two short signals and a long signal.

At the beginning of the first signal, arm 8a drops onto the portion of smaller diameter of cam 7. Under the effect of its spring 11a, rod 9a pivots about its axis so that the upper end of 10a comes to engage the helical grooves of cylinder 12, which is also rotating.

At the same time, arm 8b (corresponding to the other sliding member 9b) is lifted by cam 7, against the action of its spring 11b, and the end of lever 10b is withdrawn from the helical groove of cylinder 12. Sliding member 9b is then released, and, under the effect of spring 13b, it is caused to slide along its axis toward the right hand side of the figure.

Due to the engagement of 10a with 12, member 9a is caused to slide toward the left hand side of the drawing, and it comes into contact with abutment 14a. This releases escapement wheel 25 from projection 29. Then as the movement proceeds, the escapement wheel is again caught automatically by projection 29.

The rotation of shaft 16 that has been thus produced has caused a helical displacement of cylinder 17 (30 being engaged in the screw thread groove 27) corresponding to one step, so that the point now located opposite printing member 35 42 is now point a preceding A.

The second short signal is now transmitted. It produces the same result as just above explained, with the difference that sliding member 9a is released and pulled back by spring 13a, 40 while, on the contrary, sliding member 9b is brought into driving engagement with cylinder 12 and caused to strike finger 14b to produce the displacement of projection 29 away from escapement wheel 25.

Therefore, as a result of this second short signal, cylinder 17 is again moved forward with a helical movement of an amplitude corresponding to one step, so that the point now brought opposite printing member 42 is now point h preceding H.

The third, and last, signal of the series is a long signal.

The beginning of the operation is of course unchanged. In other words, sliding member 9b 55 is released, sliding member 9a is brought into engagement with driving cylinder 12. The end of this sliding member 9a acts on abutment 14a, and causes it to lift projection 29 away from the escapement wheel 25 for the time necessary for a further angular displacement of shaft 16. Cylinder 17 is again advanced helically a distance corresponding to one step and the point brought opposite printing member 42 is now point n preceding character N.

But, as this signal is a long signal, sliding member 9a is moved toward the left to a greater distance and its end comes to act on finger 15a, rigid with nose 31. (It should be well understood that, if the number of signals transmitted had been even, say four instead of three, the sliding member in action would have been 8b, adapted to act on finger 15b, rigid with 15a, and nose 31 would also have been pivoted.)

As a result of the lifting of nose 31, wheel 70 37 is released, and it turns through 180°, to-

gether with shaft 32. Then, the other projection of wheel 31 is caught by nose 31 and shaft 32 is stopped in this new position.

As above explained, owing to this rotation of shaft 32, a cam 38 has come to act on lever 30 so that the pointed upper end of said lever is withdrawn from the screw-thread groove of sleeve 21, whereas a finger 39, rigid with lever 30, is engaged into one of the annular grooves of sleeve 27. From this time on, a rotation of shaft 16 will produce a rotation of cylinder 17 about its axis, without any axial displacement.

The next series of signals is now transmitted. As above stated, in the example chosen, it corresponds to a short signal and a long signal.

The short signal produces the following results, in a manner analogous to that above fully described.

Sliding member 9a is released, and sliding member 9b brought into operative connection with cylinder 12. Finger 14b is actuated, producing the disengagement of projection 29 from escapement wheel 25. Shaft 16 is allowed to turn through an angle corresponding to one step. In view of the engagement of finger 39 in the annular groove of sleeve 21, cylinder 17 turns about its axis, without any axial displacement. The letter brought opposite printing member 42 is now N.

The next signal is a long signal. During the first part of this long signal, the above described operations are again repeated, and this finally brings character O opposite printing member 42. as desired.

The second part of this long signal produces, as above, a further displacement of sliding member 9a, which acts on abutment 15a, releases wheel 31 for one half revolution and permits shaft 32 to turn through one half revolution.

The operations resulting from this operation have been fully described above. Briefly stated, they are the following:

Cam 40 causes the printing member 42 to operate with character U, to print this letter;

Cam 43 causes escapement wheel 25 to be temporarily disengaged from projection 29, thus permitting free rotation of shaft 16 for a short time;

Cam 38 has caused arm 39 to be withdrawn from the corresponding groove of sleeve 27.

Spring 28 can thus bring back cylinder 17 into its initial position.

Of course, cylinder 17 can bring characters corresponding not only to letters but also to all kinds of signs.

In the above description, it has been assumed that the coordinates of the different characters to be printed or otherwise recorded are rectangular coordinates. But of course this has no limitative value. Any system of coordinates may be employed according to the present invention.

Likewise, instead of using, for transmission, series of signals the number of which characterizes the transmission, I might, without departing from the principle of the invention, characterize the signals by their lengths. Each letter or other sign transmitted would be characterized by a different length of signal.

When the letters or signs transmitted are characterized by the numbers of signals transmitted, a considerable simplification is obtained as a consequence of the fact that there are only two different lengths of signals, to wit short signals and long signals, as above described. The mechanisms to be used are then much simpler.

It is again pointed out that the system according to the invention ensures a reduction of the length or number of signals to be transmitted since, instead of transmitting two values, corresponding to two coordinates, I transmit only the smaller of these two values, and the difference between the smaller and the greater.

Of course the apparatus, instead of printing the message transmitted on a paper band, might print it on pages.

In a general manner, while I have, in the above description, disclosed what I deem to be practical and efficient embodiments of the present invention, it should be well understood that I do not wish to be limited thereto as there might be changes made in the arrangement, disposition, and form of the parts without departing from the principle of the present invitation as comprehended within the scope of the appended claims.

What I claim is:

1. The method of telegraphic transmission of coordinates corresponding to signs in accordance to a code, which comprises, transmitting first by means of electric signals the smaller of the two coordinates, and producing, at the receiving station a simultaneous increase of both of the two coordinates of a marking means, corresponding to the value of said smaller coordinate, transmitting by electric signals the difference between the two coordinates in question, and producing, at the receiving station, an increase of the corresponding coordinate proportional to this difference.

2. In a telegraphic transmission system, a receiving device which comprises, in combination, a cylinder having, on its surface a plurality of characters each defined by its coordinates in a rectangular system of coordinates having an axis parallel to the axis of the cylinder and another axis of coordinates perpendicular thereto, said characters being all located on the same side of a line which is the geometrical locus of all the points of equal coordinates of said surface, motor means for driving said cylinder, transmission means interposed between said motor means and said cylinder, including guiding means for said cylinder adapted to cause it to move helically with a pitch corresponding to that of said line of the system of coordinates, and other guiding means for said cylinder adapted to cause it to move with a simple rotation about its axis always in the same direction, for bringing the two guide means into and out of action, exclusively of each other, means, operative by a series of signals for moving said cylinder proportionally to the smaller of the two coordinates to be transmitted, with said first mentioned guiding means in action, means, operative by a longer signal forming the end of said series of signals, for bringing the first mentioned guiding means out of action and the second mentioned guiding means into action, and means operative by a second series of signals, corresponding to the difference between the two coordinates to be transmitted, for moving said cylinder proportionally to said difference.

3. In a telegraphic transmission system, a receiving device which comprises, in combination, a cylinder having, on its surface, a plurality of characters each defined by its coordinates in a rectangular system of coordinates having an axis parallel to the axis of the cylinder and another axis of coordinates perpendicular thereto, said characters being all located on the same side of

a line which is the locus of all the points of equal coordinates of said surface, motor means for driving said cylinder, transmission means interposed between said motor means and said cylinder, including guiding means for said cylinder adapted to cause it to move helically with a pitch corresponding to that of said line of the system of coordinates, and other guiding means for said cylinder adapted to cause it to move with a simple rotation about its axis always in the same direction, means for bringing the two guide means into and out of action, exclusively of each other, means, operative by a series of short signals, for moving said cylinder proportionally to the smaller of the two coordinates to be transmitted, with said first mentioned guiding means in action, means operative by a longer signal forming the end of said series of

short signals for bringing the first mentioned guiding means out of action and the second mentioned guiding means into action, means, operative by a second series of short signals for moving said cylinder proportionally to the difference between these two coordinates to be transmitted, with said second mentioned guiding means in action, and means, operative by a second long signal forming the end of said second mentioned series of short signals, for restoring the parts to their initial position.

5 4. A device according to claim 3 further including record supporting means, the means operative by the second long signal being adapted to effect the printing operation by the cooperation of said record supporting means with said cylinder.

CLAUDE JEAN CLAYETTE.
